UNITED STATES PATENT OFFICE

CHARLES C. SPREEN, OF DETROIT, MICHIGAN, ASSIGNOR TO KELVINATOR CORPORATION, OF DETROIT, MICHIGAN, A CORPORATION OF MICHIGAN

MECHANICAL REFRIGERATION

Application filed June 3, 1926, Serial No. 113,472. Renewed March 6, 1930.

My invention relates to mechanical refrigeration, and particularly to expansion units of the type peculiarly suitable for domestic mechanical refrigeration apparatus, and the 5 principal object of my invention is to provide a new and improved expansion unit of this type. In the drawings accompanying this specification and forming a part of this application I have shown, for purposes of illustration, certain forms which my invention may assume. In these drawings:

Figure 1 is an end elevation of one form which my invention may assume,

Figure 2 is a side elevation of the expansion unit shown in end elevation in Figure 1,

Figure 3 is a view similar to Figure 2 showing a second form which my invention may assume,

Figures 4 and 5 are views similar to Figures 1 and 2 showing a third form which my invention may assume, while

Figure 6 is a view similar to Figure 5 showing a still further form which my invention may assume.

The embodiment of my invention shown in Figures 1 and 2 comprises a refrigerator cabinet 11 provided with a refrigerating chamber 12 in which is mounted, by means of a cradle 13 secured to the top wall of the 30 refrigerator cabinet 11, an expansion drum 14 of the flooded type provided at its front end with a reduced extension 15, carrying on the end of this extension 15 inlet and outlet shut-off valves 16 and 17 controlling 35 the flow of refrigerant into and from the drum 14, containing means (not shown) for controlling the flow of liquid refrigerant into the drum 14, and comprising also an enlarged section 18 serving as a header from 40 which depend a plurality of looped expansion tubes 19 arranged with both ends of each tube connected to the header 18, with the tubes 19 encircling and supporting a plurality of vertically aligned containers or 45 sleeves 20 each adapted to receive a receptacle 21 for the production of artificial ice under the action of the refrigerant within the expansion coil, and with the tubes 19 diverging from each other in the direction of extent of 50 the header 18 and containers or sleeves 20 and

receptacles 21 to thus permit the tubes to subtend along the containers or sleeves 20 and receptacles 21 a distance greater than the length over which the tubes 19 may be connected to the header 18 whereby, with receptacles 21 of a length greater than the header 18, the usual practice in order to secure greater capacity in the receptacles 21, the refrigeration is extended more nearly over the entire extent of the receptacles 21 55 and the formation of ice in the receptacles 21 occurs comparatively uniformly throughout the entire length of the receptacles 21 instead of being almost entirely confined to the center portion of the receptacles as heretofore. 60

In Figure 3 I have shown a second form which my invention may assume similar in all respects to the form of Figures 1 and 2 except that for the straight inclined tubes 19 70 of the embodiment shown in Figures 1 and 2 I have substituted tubes 22 diverging by means of offsets 23 provided just below the header 18 and then extending vertically throughout substantially the entire height of the ice receptacle means to even more completely spread the refrigerating action along the entire length of all of the receptacles 21. 75

In Figures 4 and 5 I have shown the general form of my invention shown in Figures 80 1 and 2 applied to an expansion unit constructed for a refrigerating chamber 23 of greater width and less height than the refrigerating chamber 12 of Figures 1 through 3, and comprising coils 24 extending to a lesser 85 distance below the drum 14 and to a greater distance laterally of the drum 14 to thus provide for two vertically aligned containers 20 directly below the drum 14 and two additional containers 20 one in each of the lateral extensions of the tubes 24, the tubes 24 diverging in the same manner as the tubes 19 of the form of my invention shown in Figures 1 and 2. 90

In Figure 6, I have shown a still further form which my invention may assume similar in all respects to the form of Figures 4 and 5 except that it substitutes for the tubes 24 of the form of Figures 4 and 5 tubes 25 95 100

of the general contour of the form of my invention shown in Figure 3.

From the above description it will be obvious to those skilled in the art that I have provided improved expansion units. At the same time it will also be apparent to those skilled in the art that the embodiments of my invention herein shown and described may be variously changed and modified without departing from the spirit of my invention or sacrificing the advantages thereof. It will therefore be understood that the disclosure herein is illustrative only and that my invention is not limited thereto.

15 I claim:

1. A refrigerant expansion unit comprising an elongated horizontally disposed header, and refrigerant vaporization tubes extending from said header, the bottom portion of some of said tubes being disposed beyond the ends of said header.

2. A refrigerant expansion unit comprising a header, pipe loops extending from said header in aligned relation, a sleeve within said pipe loops, said pipe loops extending adjacent one wall of said sleeve and arranged to contact thermally, therewith a greater distance than the shortest distance between the edges of said sleeve wall projecting transversely to the loops.

3. A refrigerant expansion unit comprising a header, tubes communicating with said header on opposite sides thereof, each of said tubes extending in a divergent direction relative to the other of said tubes, and vertically aligned sleeves supported by and contacting with one side of each of said tubes, said tubes having a portion in thermal contact with and traversing said sleeves at an angle to the vertical axis therethrough.

4. A refrigerant expansion unit comprising an elongated header, a plurality of conduits having end portions communicating with the header and having aligned portions disposed transversely to the longitudinal axis thereof in a region bounded by planes parallel to said axis, said end portions and said aligned portions being distributed throughout unequal expanses of space.

5. A refrigerant expansion unit comprising an elongated header, a plurality of conduits having end portions communicating with the header and having aligned portions disposed transversely to the longitudinal axis thereof in a region bounded by planes parallel to said axis, said aligned portions being distributed throughout a greater expanse of space longitudinally of the header than the end portions.

6. A refrigerant expansion unit comprising a header, a plurality of conduits having end portions communicating with the header on opposite sides of a central vertical plane of reference and having aligned portions intermediate the end portions in a region

bounded by parallel planes at one side of the header, said end portions and said aligned portions being distributed throughout unequal expanses of space.

7. A refrigerant expansion unit comprising a header, a plurality of conduits having end portions communicating with the header on opposite sides of a central vertical plane of reference and having aligned portions intermediate the end portions in a region bounded by parallel planes at one side of the header, said aligned portions being distributed throughout a greater expanse of space longitudinally of the header than the end portions.

80 In testimony whereof I hereunto affix my signature.

CHARLES C. SPREEN.
